UNITED STATES PATENT OFFICE.

ROBERT A. BROOKS, OF CHICAGO, ILLINOIS.

FLUSHING APPARATUS.

1,315,207.

Specification of Letters Patent.

Patented Sept. 9, 1919.

Application filed October 27, 1917. Serial No. 198,811.

To all whom it may concern:

Be it known that I, ROBERT A. BROOKS, a citizen of the United States, residing at Chicago, in the county of Cook and State of Illinois, have invented certain new and useful Improvements in Flushing Apparatus, of which the following is a specification.

The siphonic device which is an important part of my present invention may be regarded as a modification of and improvement upon a siphonic device for flushing water closets described in my Patent No. 1,265,601, May 7, 1918. One object of the present invention is the production of an improved siphonic flushing device having the mode of operation hereinafter described, and having structural advantages in the way of simplicity, strength, durability, convenience and economy of construction, certainty of operation, etc., rendering it highly useful and desirable, and which shall include a certain novel and efficient arrangement for producing an afterwash or refill of the closet bowl after the termination of the flushing operation. A further object of my invention is the provision of means whereby my device is adapted for installation either in a situation where the supply main supplies water at high pressure, or where the water is supplied at a relatively low pressure. With the foregoing and incidental objects and advantages in view I have devised and invented the flushing apparatus illustrated in the accompanying drawings and hereinafter described, the essential elements of my invention being recited in the appended claims.

Of the drawing Figure 1 is a central vertical section through one of my novel siphonic flushing devices arranged for delayed actuation by means of the release or raising of a closet seat; Fig. 2 is a view of the upper part of the same showing a modified form of lever arranged for direct actuation; Fig. 3 is a view, somewhat diagrammatic, of a battery of connected closets equipped with my new flushing devices, showing an auxiliary or supplementary tank connected to the supply pipe, whereby the installation is adapted to be used in connection with a service pipe under relatively low pressure; and Figs. 4 and 5 are cross-sections of the flushing device, Fig. 4 being taken in a plane lying immediately above the piston 24, and Fig. 5 in a plane lying

immediately above the check-valve seat at the bottom of the tank 17, the check-valve itself not being shown.

The same letters of reference indicate the same parts in all the figures of the drawings.

Referring to Fig. 3 of the drawings, water from the service pipe 1 is admitted to the master tank 2 through a float-controlled valve 3 which is preferably of large capacity, but of any desired and suitable construction. As illustrated, the tank may be conveniently arranged at the height at which tanks used in connection with a siphonic flushing valve are usually arranged, — say about seven or eight feet above the floor, although by employing larger flushing pipes, the height may be less, if desired. Communicating with the bottom of the master tank is a line of piping 4 constituting a common supply pipe which extends horizontally through or adjacent the rear of all the closets of the system. At intervals in the line of closets, say at every twentieth or thirtieth closet, supplementary or reserve tanks 5 are arranged in unrestricted communication with the piping 4, the number of these tanks being dependent on the supply of water afforded by the service pipe 1, and also, to some extent, by the size of the supply pipe 4 and fittings, the number of closets in the installation, and the frequency of their use.

In the line of piping 4 there is arranged in each closet one of my new siphonic flushing devices A, Figs. 1 and 2. The lower part of each device consists of a casing 6 provided with a cap plate 7 securely bolted thereto, the casing being provided with opposite threaded bosses 9—9 by which it is secured to sections of the piping 4. The bottom of the casing is provided with a drain plug 30 and formed with a depending integral screw-threaded connection 10 by which it is secured to the top of the flushing pipe 11. In alignment with the flushing pipe and secured in a threaded seat on the inside of the casing is a pipe 12 which constitutes the upper portion of the descending leg of the siphon, and the proportions and arrangement of the parts of the flushing device and master tank are such that the normal water-level in the former will be a short distance below the top of the pipe 12. The cap plate 7 is formed with a depending tube 13 concentric with the pipe 11.

12, the lower part of this tube being cut away to form large ports 14 separated by guide lugs 15,—see Fig. 4. In alinement with the tube 13 a threaded socket on the 5 upper side of the plate 7 supports a short tube 16 which forms a continuation of the tube 13. The upper end of the tube 16 is threaded, and engages and supports a small tank 17 which constitutes the reservoir of a 10 retarding and repelling device. The tank 17 and casing 6 are further connected by a second short pipe 18 making screw-threaded engagement at its bottom with a threaded orifice in the top of the cap plate 7, and at 15 its top secured by a nut 18^a to a seat in the bottom of the tank 17.

In axial alinement with the tube 16 (the upper end of which lies a short distance below the bottom of the tank 17) is arranged 20 a short tube or stand-pipe 19 secured to the bottom of the tank and closed at its top except for a small vent orifice 20. The tank also communicates through the interior of the tube with the space therebelow by 25 means of a drain opening or refill port 21 just above the bottom of the tank. The exterior of the tube 19 is threaded to support an adjusting nut 22, and between this nut and a valve seat at the bottom of the tank 30 is arranged a check-valve 23,—see Figs. 1 and 5,—which permits a regulated flow of water upwardly through the valve openings 23^a, and prevents downward flow of the water therethrough.

35 Siphonic action in my new flushing device is positively initiated by the downward movement of a piston 24 arranged to reciprocate in the lower portion of the casing 6 as a piston chamber. This movement of 40 the piston forces the water underneath it through the ports 14 upwardly between the tubes 12 and 16, the larger part of it filling the latter tube and initiating the flush, and a portion of it passing past the check 45 valve 23 (and to a small extent through the vent orifice 20 and refill port 21) to the inside of the tank 17, filling it to a level a certain distance above the vent orifice 20. After the piston 24 has seated the siphonic 50 flow from the piping 4 through the ports 14 and between the tubes 12 and 16 into the latter tube and flushing pipe 11 has been established, the check valve 23 will descend upon its seat, and thereafter water 55 from the tank 17 will gradually escape, both through the vent orifice 20 and refill port 21, until the level of the water sinks to the vent orifice, when air will enter and break the siphon. The remainder of the 60 water in the tank will then escape gradually through the refill port and constitute the refill flow. The amount of water which passes into the tank and consequently the length of the flushing action is governed by

the position of the adjusting nut 22, which 65 serves as a stop for the check-valve 23, and thus controls and regulates the amount of water which may pass around the valve. It may here be explained that the fit of the piston rod 26, hereinafter described, in the 70 pipe 18 is as close as it can be made without causing undue friction so that the passing of water around the rod does not materially affect the action which has just been described.

75 In the form of my device shown in Fig. 1 the normal position of the piston 24 is at the bottom of the cylinder, and in the use of the closet the depression of the closet seat (which is normally slightly raised) acts 80 through suitable connections in a well-known manner to depress one end of an intermediately pivoted operating lever 25 which at its other end is connected with the piston 24 by the piston rod 26 above-mentioned and which is arranged in the pipe 18. The piston preferably is lifted somewhat above the bottom of the openings into the cylinder of the piping 4, so that such water as is withdrawn from between the 85 tubes 12 and 16 into the space below the piston is immediately returned by a free flow from such piping through the ports 14 to restore the water level in the siphon to its normal level, and the subsequent release or raising of the seat permits the piston and associated parts (which are preferably sufficiently heavy to return positively by force of gravity) to descend to their 90 normal position, thus causing a flushing operation as above described. The piston is preferably loose fitting, however, and even if the actuating connections should be so adjusted that the piston when lifted did not clear the pipe openings, the water level between the pipes 12 and 16 would very 95 quickly be restored by leakage past the piston. A spring suitably connected may of course be used if necessary to effect the 100 return of the piston and associated parts to 105 normal position.

110 With the form of operating connections shown in Fig. 2, the piston is normally held in uppermost position by means of a weighted lever 27 pivoted on a bracket 28 secured 115 to the tank 17. By means of a chain pull the lever may be rocked to depress the piston, effecting an immediate flush of the 115 closet, as before.

120 It will be understood that while the improved form of flushing device which has just been described is well adapted for use in installations where the pressure is high and capable of supplying to a master tank connected to separate flushing devices in 125 the several closets an abundant flow of water, sufficient to directly supply the maximum number of devices which are liable to

be flushed at any one time, yet, in order to enable it to be used under conditions where a high pressure is not available, I have provided the supplementary or auxiliary tanks

5 above mentioned, whereby the flushing devices may be successfully used in situations where the pressure is relatively low, this arrangement being particularly useful in the installation of a large battery of closets.

10 Moreover, the use of auxiliary tanks enables the size of the piping 4 and fittings to be reduced to a minimum, since the supply of water which they afford adjacent any particular device being flushed relieves

15 measurably the demand which a flow from the master tank alone would otherwise supply. Such tanks also enable my devices to be used in installations,—particularly those consisting of a large number of closets,—in

20 which the flow of water which may be required for the flushing of a number of closets at once is liable to exceed the maximum amount of water which can be supplied by the service pipe.

25 Preferably a shut-off valve is provided at the master tank and at suitable points in the line of piping 4 by means of which the water can be cut off from a part or all the flushing devices, for repairs and extensions or as a protection against frost. The flushing devices can be drained whenever desired by means of the siphons and drain plugs.

I claim:

30 1. In a flushing device, a supply pipe, a casing inclosing a piston chamber in free communication at its upper end with said supply pipe, a siphon the ascending leg of which has ported communication with the lower end of said piston chamber, and a piston in said chamber arranged to force water through said port and siphon during the first portion of its downward stroke, and at the conclusion thereof place the space thereabove in communication through said port with the siphon.

35 2. In a flushing device, a supply pipe, a casing inclosing a piston chamber in free communication at one end with said supply pipe, a siphon the ascending leg of which has ported communication with the other end of said piston chamber, and a piston in said chamber arranged to force water through said port and siphon during the first portion of its stroke from the end opposite said port, and at the conclusion thereof place the space therein on the opposite side of the piston in communication through said port with the siphon.

40 3. In a flushing device, a supply pipe, a casing inclosing a piston chamber extending downward below the level of the water supply pipe, and at its upper end in free communication therewith, a siphon the ascending leg of which is in communication with

the lower end of said piston chamber, and a piston in said piston chamber arranged to force water through said ascending leg of the siphon to initiate a flush. 65

4. In a flushing device, a supply pipe, a casing inclosing a piston chamber in free communication at its upper end with said supply pipe, a tube extending below the bottom of said casing to form a flushing pipe and extending vertically through and above the bottom thereof to form the upper portion of the descending leg of a siphon, a second tube arranged to be sealed at its top surrounding the upper portion of said first-mentioned tube and extending into and opening at its bottom within said casing and constituting the ascending leg of the siphon, and an orificed piston in said piston chamber surrounding said second tube and arranged to force water through the siphon passages to initiate a flush. 70 75 80 85

5. In a flushing device, a supply pipe, a casing inclosing a piston chamber in free communication at its upper end with said supply pipe, a tube extending below the bottom of said casing to form a flushing pipe 90 and extending vertically through and above the bottom thereof to form the upper portion of the descending leg of a siphon, a second tube concentrically surrounding the upper portion of said first-mentioned tube 95 extending into and opening at its bottom within said casing and constituting the ascending leg of the siphon, a tank arranged with its bottom wall lying above the top of said last mentioned tube and secured to the top of said second tube and having a drain port in alinement with said second tube, and an orificed piston in said piston chamber surrounding said second tube and arranged to force water through the siphon 100 105 passages and also into said tank.

6. In a flushing device, a supply pipe, a casing inclosing a piston chamber in free communication at its upper end with said supply pipe, a tube extending below the bottom of said casing to form a flushing pipe and extending vertically through and above the bottom thereof to form the upper portion of the descending leg of a siphon, a second tube concentrically surrounding the upper portion of said first-mentioned tube extending into and opening at its bottom within said casing and constituting the ascending leg of the siphon, a tank arranged with its bottom wall lying above the top of said last-mentioned tube and secured to the top of said second tube, and having restricted communication therewith, a third tube opening at its top into said tank and at its bottom into said casing, an orificed piston in said piston chamber surrounding said second tube and arranged to force water through the siphon passages and also into said tank, and 110 115 120 125

a piston rod connected to said piston and arranged within said third tube.

7. In siphonic flushing apparatus, a retarding and refilling device comprising a tank arranged above the top of the siphon, a passage in communication with the top of the siphon and terminating inside the tank at a vent orifice above the bottom thereof, a drain opening leading from the bottom of the tank into the discharge leg of the siphon, and means for filling said tank with water above the level of said vent opening at the beginning of each flushing operation.

15 8. In siphonic flushing apparatus, a retarding and refilling device comprising a tank arranged above the top of the siphon, a stand pipe communicating with the top of the siphon and arranged within said tank and having a vent orifice at its top and a drain port at its bottom arranged to drain into the discharge leg of the siphon, and means for supplying said tank with a charge of water to seal said vent orifice and drain opening at the beginning of each flushing operation.

9. In siphonic flushing apparatus, a retarding and refilling device comprising a tank arranged above the top of the siphon, 30 a stand pipe communicating with the top of the siphon and arranged within said tank and having a vent orifice at its top and a drain port at its bottom arranged to drain into the discharge leg of the siphon, a 35 check-valve between the top of the siphon and the tank permitting a governed flow of water into the tank, and means for forcing a charge of water through the siphon passages to initiate a flush and supply the tank 40 with a charge of water for sealing communication between the tank and siphon.

10. In siphonic flushing apparatus, a retarding and refilling device comprising a tank arranged above the top of the siphon, 45 a stand pipe communicating with the top of the siphon and arranged within said tank and having a vent orifice at its top and a drain port at its bottom arranged to drain into the discharge leg of the siphon, an adjusting nut screw-threaded in said stand pipe, a check valve loosely mounted on said stand pipe between said nut and its seat at the bottom of the tank for governing the flow of water into the tank, and means for 55 forcing a charge of water through the siphon passages to initiate a flush and supply the tank with a charge of water for sealing communication between the tank and siphon.

60 11. In flushing apparatus a siphon having a vertical open-top tube constituting its descending leg, and a concentric open-bottom tube constituting its ascending leg, a tank arranged above said siphon tubes, the

bottom wall of the tank constituting the 65 top of the siphon, a vent tube in said tank communicating with the top of the siphon and with a vent opening in said tank above the bottom thereof, the tank also communicating with the top of the siphon through 70 a drain port opening above said first-mentioned tube, and means for filling said tank with water above the level of said vent opening at the beginning of each flushing 75 operation.

12. In flushing apparatus a siphon having a vertical open-top tube constituting its descending leg, and a concentric open-bottom tube constituting its ascending leg, a tank arranged above said siphon tubes, the 80 bottom wall of the tank constituting the top of the siphon, a short stand pipe in said tank in alinement with said first-mentioned tube, said stand pipe having a vent opening at its top and a drain port adjacent 85 the bottom of the tank, and means for filling said tank with water above the level of said vent opening at the beginning of each flushing operation.

13. Flushing apparatus for a large battery of water-closets comprising a single master tank, means for maintaining a constant level of water therein, a common line of supply piping extending through all the closets, flushing devices individual to the 90 closets and each arranged to flush its particular closet through direct flow from the supply piping, and supplementary tanks arranged at intervals in said line of supply piping and in free communication there- 95 with. 100

14. In a flushing device for water-closet apparatus including means for maintaining a supply of water at a constant level, a casing communicating with the water supply 105 and having a tubular extension 16 extending above the water level, tubular piping secured to and extending below the bottom of said casing to form a flushing pipe 11 and extending vertically through and above 110 the bottom thereof to form the uppermost portion 12 of the descending leg of a siphon, a tubular member 13 continuous with the tubular extension 16 secured to and extending 115 downwardly within said casing and opening into the casing adjacent its bottom, the space between said tubular extension 16 and tubular member 13 and said portion 12 of the piping constituting the ascending leg of the siphon, and means 120 within the casing for forcing water through the opening at the bottom of said tubular member 13 into and through said space to initiate a flush.

15. In apparatus for flushing water 125 closets including a common master tank for maintaining a supply of water at a constant level and a supply pipe in commun-

cation therewith, a flushing device individual to each closet comprising a casing enclosing a piston chamber in communication with said supply pipe, a siphon the ascending leg of which is in communication with the lower end of said piston chamber and the descending leg of which is continuous

with the flushing pipe and the top of which is above the water level of the system, and a piston in said piston chamber arranged to force water through said ascending leg of the siphon to initiate a flush.

ROBERT A. BROOKS.
